CLAIM

The ornamental design for an automatic pencil, substantially as shown and described.

DESCRIPTION

FIG. 1 is a front elevational view of an automatic pencil showing our new design with the writing point in the retracted position;

FIG. 2 is a right side elevational view thereof, the left side elevational view being the mirror image thereof;

FIG. 3 is a rear elevational view thereof;

FIG. 4 is a front elevational view thereof with the writing point in the protracted position;

FIG. 5 is a top plan view thereof; and

FIG. 6 is a bottom plan view thereof.
